UNITED STATES PATENT OFFICE

GEORGE B. RAYBURN, OF LOS ANGELES, CALIFORNIA

CAP

Application filed October 13, 1930. Serial No. 488,527.

This invention relates generally to a cap or caps which will hold the hair of a male or female in proper position and is especially useful for athletes, motorists, factory workers, and in fact for any person requiring a light, cool, comfortable head covering which will have a neat appearance, and prevent the hair from falling into the eyes, and particularly to an open work cap of this type which is constructed of a single blank of flexible resilient rubber.

It is an object of this invention to provide a cap of the type described, which may be easily packed and transported and folded so as to occupy a little space, which can be produced at a low cost, and which is light and comfortable when worn, and which readily adjusts itself to different sizes and shapes of heads, without the adjustment of buckles, straps or the like.

It is also an object of this invention to provide a cap of the type described which is cut from a single blank of flat rubber sheet, in such a manner that a net work of pliant, resilient, flexible, interconnected strips is formed which readily accommodates the contour of the head, and retains the cap in comfortable, non-binding position upon the head.

Further features of novelty and advantage, and other objects of the invention, its nature, and its composition and arrangement and combination of parts will be readily understood by any one acquainted with the art to which this invention relates, upon consulting the following descriptions of the drawings, in which:

Figure 1 is a view of my improved cap in position upon the head of a person.

Figure 2 is a plan view of the cap in contracted position showing the manner of formation thereof.

Figure 3 is an edge view of Figure 2.

Referring to the drawings in detail it will be seen that I construct my improved cap of a flat, flexible, pliant, resilient rubber sheet of circular form generally designated by the numeral 5. A plurality of cut out portions 6 equally spaced circumferentially, form a border 7. The cut out portions 6 are substan-

tially tapered in a counter-clockwise direction as at 8, adjacent cut out portions defining the connecting strips 9, which are directed also in a counter-clockwise direction. At the center of the sheet designated 10 there is a plain uncut area of circular formation from which lead a series of cuts or slits 11, substantially concentrically spaced about the area 10, which lead therefrom in a clockwise direction with respect thereto, and they have a curvature which leads them toward the border 7, preferably at or beyond a point of said border corresponding to a like point of the circular area 10, though said arrangement may be varied. In the embodiment shown in the drawings, the slits 11 are discontinuous as at 12 and 13, the idea being to form a plurality of flexible strips 14 radiating from the circular portion 10 having interconnected members 15, and members 16 outside of the members 15 which connect directly with the strips 9 shown in Figure 1. The strips 15 and 16 are continued completely around the cap, the cut out portions 6 being expanded as shown in Figure 1, and the strips defined by the slits 11 stretched apart as shown in Figure 1 when the cap is placed upon the head. The strips 9 are bisected by a long and a short slit which follow the curvature substantially of the slits 11 to form the loops or meshes inward of the cut out portions 6 which are between the strips 15, 16 and 14. The inner meshes are formed by the strips 14 and the strip 15 and the circular portion 10.

Referring to the strip S in Figure 2 it will be seen that a short slit A defines one side thereof, a long slit B bisects it, and a medium long slit C defines the other side thereof, and this arrangement is continued throughout the structure, the inner portions of the strip S being further defined by companion slits 11 which form projected continuations of the slits a, b and c, with a longitudinal separation therebetween as exemplified in the drawings at the point designated d. It will now be understood how the effect illustrated in Figure 1 and described above is produced by slitting or cutting a flat circular blank of pliable, resilient and flexible rubber into

curved strips running counter-clockwise from a central circular plane area 10, and connecting these strips to other strips similarly curved and leading from the periphery of the blank inwardly in a clockwise direction, so that they are interconnected, and may stretch or be stretched to readily assume the form of the human head and resiliently engage the same. It is thought obvious that it will be understood that my improved cap may be carried about in the condition illustrated in Figures 2 and 3, which occupies very little space, and is immediately available for use. The cap is placed on the head by putting the circular area 10 against the head and drawing the border 7 about the head as desired, and the resilient curvature of the strips and the said border, and the natural elasticity thereof, will result in conforming the cap to the contours of the heads, thus retaining the hair in the desired position, without binding or requiring further adjustment.

It is to be definitely understood that I do not desire to limit the application of this invention to the particular modification set out herein to illustrate the principles thereof, and any change or changes may be made in material and structure and arrangement of parts consistent with the spirit and scope of the invention.

Having thus described the invention, what is claimed as new is:—

1. An elastic rubber cap of the type described comprising a one piece circular flat body comprising a center portion, and a plurality of curved strips projected from the center portion formed by slitting the said body, and a plurality of oppositely curved and similarly formed strips projected toward the center portion and defining a circumferential border, and joined to said curved strips to form a mesh.

2. A cap of the class described comprising a flat ring of elastic rubber, and a plurality of circumferentially spaced integral strips curved anti-clockwise and projected inwardly from said ring, and a center portion, and a plurality of integral strips curved clockwise and projected outwardly from said center portion and meeting said first mentioned strips to form a net work.

3. An elastic open work cap of the type described comprising a circular disk of elastic sheet rubber having a plurality of concentric slits running outwardly from a central island portion to points in spaced relation to the circumference of the disk, said slits being curved in a manner uniformly divergent from their common center.

4. An elastic open work cap of the type described comprising a circular disk of elastic sheet rubber having a plurality of concentric slits running outwardly from a central island portion to points in spaced relation to

the circumference of the disk, said slits being curved in a manner uniformly divergent from their common center, and other and conformably curved slits beginning and ending inwardly of the central island portion, and further slits beginning inwardly of the circumference of the disk and ending outwardly at points in spaced relation with the circumference of the disk to define a head band border.

5. An elastic open work cap of the type described comprising a circular disk of elastic sheet rubber having a plurality of concentric slits running outwardly from a central island portion to points in spaced relation to the circumference of the disk, said slits being curved in a manner uniformly divergent from their common center, and other and conformably curved slits beginning and ending inwardly of the central island portion, and further slits beginning inwardly of the circumference of the disk and ending outwardly at points in spaced relation with the circumference of the disk to define a head band border, and open spaces between pairs of said border defining slits.

In testimony whereof I affix my signature.

GEORGE B. RAYBURN.
